UNITED STATES PATENT OFFICE.

SIDNEY A. BEYLAND, OF NORTH RIDGEVILLE, OHIO, ASSIGNOR TO THE GARFORD MANUFACTURING COMPANY, OF ELYRIA, OHIO, A CORPORATION OF OHIO

HORN FOR AUTOMOBILES AND MOTOR-CYCLES.

1,158,620.

Specification of Letters Patent.

Patented Nov. 2, 1915.

Application filed October 8, 1913. Serial No. 794,144.

To all whom it may concern:

Be it known that I, SIDNEY A. BEYLAND, a citizen of the United States, residing at North Ridgeville, in the county of Lorain 5 and State of Ohio, have invented certain new and useful Improvements in Horns for Automobiles and Motor-Cycles; and I do hereby declare the following to be a full, clear, and exact description of my invention, 10 such as will enable others skilled in the art to which it appertains to make and use the same.

My invention relates to automobile or motor-cycle horns, or warning signal devices 15 employed upon such vehicles, and especially to electric warning signaling devices or horns for this use. The devices of my invention are also adapted to other uses where an audible signaling device is desired, such 20 for example, as used upon motor boats for fog signals, etc.

My invention is more particularly designed for use upon motor cycles, where the horn is mounted upon the handle bars or 25 other portion of the frame, which is already crowded with apparatus and accessories for use on the motor cycle; hence it is desirable to make the horn condensed and compact.

The motor cycle trade demands a small 30 horn which will produce a loud signal, since the motor cycles travel at a rapid pace and approach an object quickly from a distance, so that it is desirable to give ample warning in order that the road may be cleared 35 or the pedestrian warned far enough ahead to have heeded the warning before the motor cycle arrives. It is also desirable to construct the horn strong and rigid, so that it will not be injured when the motor cycle 40 is leaned against a house, fence or other object, which is frequently done when the machine is at rest. Sometimes the horn may be struck by such object inadvertently 45 or through ignorance on the part of the driver, with injury to the instrument.

I aim to produce a horn which will be compact, in which the apparatus will be condensed, which will be strong and durable and which will produce a signal that can 50 be heard at a long distance away.

Other objects of my invention and the invention itself will probably be better understood from a description of a particular horn embodying my invention.

Figure 1 illustrates an embodiment of my

invention, shown in section. Fig. 2 illustrates a rear elevation thereof with the back removed.

Referring now to the drawing and to the particular embodiment illustrated, at 3 I 60 show a frame piece, which here consists of a plate of sheet metal cut away in the center to form an opening 4. A sonorous member such as a vibratile diaphragm 5 is associated with the frame piece and extended 65 over the opening 4, being exposed from the rear of the frame piece through this opening for a purpose to be described.

At 6 I show a casing front which is perforated at 7 to form an opening for the 70 egress of sound waves. The portions of the front casing constituting the edge of this opening may be turned up, as shown at 8, for connection with a resonator 9, which may be mounted in the opening for the 75 transmission of the sound waves. In the form shown, the diaphragm is clamped between the frame piece 3 and the casing front and the three parts fastened together in any suitable way, such as by screws 10. The 80 casing front is struck out, as shown at 11, to furnish a little clearance for the diaphragm and turned over the edge of the frame piece, as shown at 12.

Suitable means are provided for operating 85 the sonorous member. In the form shown electromagnetic means perform this function. Two electromagnets are shown at 13 and 14, which are supported from the frame piece, preferably by turning up one of the 90 portions of the frame piece, which constitutes the edge of the opening 4 and connecting one end of the poles 16 of the magnets to the frame piece by any suitable means, such as screws 17. The ends 16 of the 95 poles project some little distance beyond the front end windings and are flattened off as shown at 18, presenting a flattened surface to the armature. Suitable means are provided for transmitting the energy of the 100 magnets to the diaphragm, which is here shown as an armature 19 acting as a hammer and striking upon an anvil 20 upon the diaphragm. The armature is best made rectangular in shape, its flat under surface being drawn to the flattened tops of the poles of the magnets when they are energized and the central part of the armature striking the anvil 20. The armature is supported 105 from the frame by any suitable means, such 110

as a spring 21 connected at one end to an edge 22 of the frame piece and at the other to the armature by any suitable means, such as screws 23. In the form shown, the armature is spaced from the spring 21 by studs 24 which elevate the armature above the poles for a purpose to be described. In the form shown a switch 25 controls the circuit of the magnets 13 and 14. This switch consists of a plurality of contacts, each supported from the frame by leaf springs. The armature controls this switch and in the form shown, I have extended one of these springs 28, as shown at 29, in order that it may be operated by the armature when vibrated to open said switch. An insulating stud 30 connected to the armature, engages this extended end of the spring 28. Suitable means are provided for adjusting the switch, here shown as an adjusting screw 32, engaging the upper switch spring 33. The screw is supported by the bracket 34, also supported from the frame.

The armature spring carrying its armature, the switch springs carrying their contacts and the adjusting screw bracket carrying its adjusting screw are insulated from each other by insulation 40 and these parts are connected together by some suitable means, such as a screw 41, being removable as a unit from the frame to which they are connected through a spacing member 50 by some suitable means, such as screws 52. The terminals 54 of the conductors leading to the switch 25 are also carried in this removable unitary structure, as shown in Fig. 2. A rear casing 60 is provided for covering the apparatus and is connected to the frame piece, in the form shown, by turning up from the frame piece connecting lugs 70 to which the rear casing is connected in any suitable manner. The horn may be connected to the vehicle by any suitable means, such as a bracket 80, which is here shown as a part of the frame piece.

In the operation of the horn, the circuits of the magnets are closed, including the switch 25, whereupon the magnets attract the armature 19, pulling it down, so that its plane remains substantially parallel to the plane of the diaphragm. When thus attracted, the armature strikes upon the anvil 20, which is here shown as a socket 90 on the diaphragm and an adjustable screw 91 fitting in the socket, the screw and socket bearing complementary threads. When the armature is thus drawn to its lower position, the striking of the diaphragm causes the same to sound a signal and the switch 25 is opened through the engagement of the stud 30 with the end 29 of the spring 28. When thus opened, the switch interrupts the circuit of the magnets which become deenergized and release the armature, this cycle being repeated. The rate at which it is re-

peated depends largely upon the natural rate of vibration of the spring 21.

I have illustrated this form of my invention, not with the intention of being limited thereto, but simply for the purpose of illustrating my invention. I contemplate numerous and extensive departures from the form and details of the apparatus here shown.

I claim:

1. In an automobile or motor cycle horn, the combination of a flat frame piece having a relatively large opening therein, the piece being turned up at one edge to form a support, a vibratile sonorous diaphragm, a casing front having an opening therein for the egress of sound waves, a resonator in said opening, said diaphragm being clamped between the casing front and the frame piece, means to attach said front, diaphragm and frame piece together, a pair of electromagnets including cores and windings, the magnet cores being attached at one end to said support and extending substantially parallel to the diaphragm over the opening in the frame piece, the other ends of the cores projecting beyond the windings and being cut away to form a flat surface presented to the armature, an armature for said magnets and to the rear thereof spanning the space between the projecting ends of the poles and adapted to be attracted to the sides of such ends when said magnets are energized, a spring connecting said armature to the frame piece, an electric switch controlling the circuit of the magnet including contacts, springs connected to the frame piece carrying said contacts, means to adjust said contacts supported from the frame piece, an anvil upon the diaphragm upon which the armature beats when vibrated, a cover for the apparatus supported from the frame piece and means to attach the cover to the frame piece.

2. In an automobile horn, the combination of a flat frame piece having an opening therein, the piece being turned up at one edge to form a support, a front casing, a diaphragm mounted between the casing and frame piece and exposed through the opening in the frame piece, means for operating the diaphragm including an electromagnet mounted on said support and extending substantially parallel to the diaphragm, means to connect one end of said magnet to said support with its armature operating end adjacent the center of the diaphragm, an armature to the rear of the poles of the magnet for actuating the diaphragm, said armature associated with the armature actuating ends of the magnet and means including a spring connecting the armature to the frame piece and normally positioning it out of engagement with the diaphragm and adjacent the center portion thereof.

3. In an automobile horn, the combination

of a flat frame piece having a relatively large opening therein, one of the edges of the frame piece being turned up to form a support, a vibratile sonorous diaphragm associated with the frame piece and exposed from the rear through the opening in the frame piece, means for operating said diaphragm which acts upon the same through the opening, said means including an electromagnet mounted upon the back side of the frame piece and having its core extending over the opening and the exposed part of the diaphragm and substantially parallel to the diaphragm, means to connect one end of the electromagnet to said support and normally holding it in position with the armature actuating end adjacent the central portion of the diaphragm, an armature for actuating the diaphragm controlled by said magnet mounted over the opening in the frame piece, means including a spring connecting the armature with the frame piece and normally holding the armature out of engagement with the diaphragm and with its diaphragm actuating portion over the central portion of the diaphragm, and an electric switch controlled by the armature.

4. In an automobile or motor cycle horn, the combination of a sheet metal supporting member having an opening therein, one edge of the supporting member being bent upwardly to form a magnet support, a diaphragm associated with the supporting member and exposed through the opening therein, means for operating said diaphragm including an electromagnet mounted upon said magnet support and extending substantially parallel to the diaphragm with its free or armature actuating end toward the center of the diaphragm, an armature for actuating the diaphragm operated by said magnet, and an electric switch governing the flow of current through the magnet controlled by the armature.

45 5. In an automobile or motor cycle horn, the combination of a sheet metal supporting member having an opening therein, one of the edges of said member being turned up to form a magnet support, a diaphragm associated therewith, electromagnetic means mounted on said support with its core and windings substantially parallel to the diaphragm and with its free end toward the center of the diaphragm, the armature of said electromagnet being fastened to the supporting member opposite the magnet and normally held in position to the rear of the core of said magnet, and an electric switch controlled by the magnet.

6. In an automobile or motor cycle horn, the combination of a sheet metal supporting member having an opening therein, the edge of said member being turned up to form a magnet support, an armature associated with said opening, electromagnetic means

including a core, an armature and coils mounted on said core, said electromagnetic means being mounted on said magnet support to the rear of the frame piece with the core of the magnet substantially parallel to the diaphragm and the free or armature actuating end of the magnet extending toward the center of the armature, means to support said armature holding the same normally in position to the rear of the magnet core, and an electric switch controlled by said armature.

7. In an automobile or motor cycle horn, the combination of a sheet metal flat supporting member having an opening therein, one of the edges of said supporting member being turned back to form a magnet support to the rear of the flat supporting member, a diaphragm associated with said member, a magnet mounted on said magnet support with its free or armature actuating end toward the center of the diaphragm, an armature adapted when operated by said magnet to cause the actuation of said diaphragm and means to connect said armature to said flat supporting member, said means normally holding said armature in position to the rear of the core of the magnet.

8. In an automobile or motorcycle horn, the combination of a flat frame piece having an opening in the central portion thereof, a sonorous diaphragm, means to connect said diaphragm to the front of the frame piece with the diaphragm extending over the opening therein, a pair of electromagnets mounted on the back side of the frame piece with their cores extending parallel to the diaphragm, means to connect one end of each of the cores to the frame piece adjacent the periphery of the frame piece, said cores extending toward the center of the diaphragm and being free at the ends adjacent the center thereof, a magnet winding on the intermediate portion of each core, a flat armature operated by said electromagnets, means to connect said armature to the frame piece, said magnet cores being provided with polar extensions projecting between the armature and the diaphragm, the adjacent faces of the armature and polar extensions being parallel, a pin through which the armature actuates the diaphragm projecting through the opening in the frame piece and adapted to be struck by the armature, and a switch adapted to be connected in the circuit of the electromagnetic means mounted on the frame piece comprising a pair of contacts controlled by the armature.

9. In an automobile or motorcycle horn, the combination of a flat sheet metal frame piece having an opening in the central portion thereof, a disk-shaped metallic sonorous diaphragm, means to connect said diaphragm to the front of the frame piece in

cluding a casing front and a plurality of bolts or screws, said casing front being provided with an opening for the egress of sound waves, a resonator in said opening, a pin projecting through the opening in the frame piece through which the diaphragm is operated, said pin being normally held perpendicular to the diaphragm, a flat vibratile armature for striking one end of the pin, a spring normally holding said armature away from said pin and for returning the armature to normal position when it has been moved to strike said pin and released, means to connect the armature and spring to the back of the frame piece, a pair of electromagnets for operating said armature and causing it to strike the pin to cause the vibration of the diaphragm, said magnets comprising a pair of cores and windings thereon intermediate the ends thereof, means to connect one end of each of said cores to the frame piece adjacent the periphery thereof, the other ends of said cores extending from the windings to form polar extensions positioned between said armature and said diaphragm, the adjacent faces of the armature and polar extensions being parallel, said magnets when thus mounted on the frame piece being parallel to the diaphragm and with their free or armature actuating ends adjacent the center of the diaphragm, and an electric switch adapted to be connected in the circuit of said magnets mounted on the back of the frame piece controlled by said armature.

10. In an automobile or motorcycle horn, the combination of a flat frame piece having an opening therein, a casing front having an opening therein for the egress of sound waves, a sonorous diaphragm connected between the frame piece and the casing front, a flat armature adapted when operated to actuate the diaphragm, means including a spring to connect said armature to the frame piece, magnets for controlling the armature mounted on said frame piece parallel to the diaphragm and with the ends of their cores between the armature and the diaphragm, said armature being behind the magnet cores, and means to mount said magnets on said frame piece.

11. In an automobile or motorcycle horn, the combination of a frame piece having an opening therein, a casing front, a sonorous diaphragm between the front and frame piece, a flat armature adapted when actuated to operate the diaphragm, means including a spring to connect said armature to the back side of the frame piece, electromagnets parallel to the diaphragm, and means to mount said electromagnets upon the back side of said frame piece, the cores of said magnets extending beyond the windings, the under face of said armature being parallel to the core of said magnets, and behind

the same, and an electric switch controlled by said armature.

12. In an automobile horn, the combination of a flat frame piece having an opening in the central portion thereof, a sonorous diaphragm extending over said opening and means to connect the same in front of the frame piece, the diaphragm being exposed through the opening in the frame piece, an electromagnet supported from the frame piece and extending substantially parallel to the diaphragm with its free or armature actuating end toward the center of the diaphragm, a polar extension extending from the free end of the magnet, an armature for said magnet adapted to be operated by the magnet, means to support the armature from the frame piece, said armature being back of said polar extension and means to transmit blows from the armature to the diaphragm.

13. In an automobile horn, the combination of a flat frame piece having an opening in the central portion thereof, a sonorous diaphragm, means to mount the diaphragm on the front of the frame piece with the diaphragm extending over said opening, an electromagnet, means to connect the magnet to the back side of the frame piece with the magnet extending substantially parallel to the diaphragm and having its free or armature actuating end adjacent the opening in the diaphragm, an armature for said magnet, means to support the armature from the frame piece, a polar extension extending from the free end of the magnet between the armature and the diaphragm, the adjacent surfaces of the polar extension and the armature being parallel to each other and to the diaphragm, and means to transmit blows from the armature to the diaphragm.

14. In an automobile horn, the combination of a flat frame piece having an opening in the central portion thereof, a sonorous diaphragm, means to mount the diaphragm on the front of the frame piece extending over the opening in the frame piece, magnet supporting means integral with the frame piece and substantially perpendicular thereto, a magnet supported by the magnet supporting means extending parallel to the diaphragm with its free or armature actuating end over the opening in the diaphragm, an armature for said magnet, means to support the armature from the frame piece, an electromagnetic switch controlled by the armature, a polar extension extending from the free end of the magnet between the armature and the diaphragm, the adjacent faces of the armature and polar extension being parallel to each other and means to transmit blows from the armature to the diaphragm.

15. In an automobile motorcycle horn, the combination of a flat frame piece having an opening therein, a casing front having an

- opening therein for the egress of sound waves, a sonorous diaphragm connected between the frame piece and the casing front, a flat armature adapted when operated to 5 actuate the diaphragm, a spring for returning the armature to normal position after it has been deflected therefrom and released, means to connect the spring and armature to the frame piece, a magnet for controlling 10 the armature mounted on said frame piece parallel to the diaphragm with the end of its core between the armature and the diaphragm, said armature being behind the magnet core, and means to mount said magnet on said frame piece.
16. In an automobile or motorcycle horn, the combination of a frame piece having an opening therein, a sonorous diaphragm and means to connect the diaphragm on the front 20 of the frame piece and over the opening therein, means to operate the diaphragm through the opening in the frame piece including a flat armature adapted when actuated to cause the vibration of the diaphragm, spring means normally holding the 25
- armature away from the diaphragm, adapted to yield when the armature is moved toward the diaphragm and to return the armature to normal when the armature is released, means to connect the spring and armature to the back side of the frame piece, a pair of electromagnets and means to mount said electromagnets upon the back side of the frame piece with their cores extending substantially parallel to the diaphragm, the 30 cores of said magnets extending between the armature and the diaphragm, adjacent faces of said core extensions and armature being parallel to each other and to the diaphragm and an electric switch controlled by the 35 armature supported from the frame piece adapted to be connected in the circuit of the magnets.
16. In an automobile or motorcycle horn, the combination of a frame piece having an opening therein, a sonorous diaphragm and means to connect the diaphragm on the front 40 of the frame piece and over the opening therein, means to operate the diaphragm through the opening in the frame piece including a flat armature adapted when actuated to cause the vibration of the diaphragm, spring means normally holding the 45

In witness whereof I have affixed my signature in the presence of two witnesses this third day of October, 1913.
